UNITED STATES PATENT OFFICE.

HENRY L. SHALER, OF DEEP RIVER, CONNECTICUT, ASSIGNOR OF ONE-HALF
TO SIMEON H. JENNINGS, OF SAME PLACE.

DIE FOR FORMING AUGER-HEADS.

SPECIFICATION forming part of Letters Patent No. 403,296, dated May 14, 1889.

Application filed February 25, 1889. Serial No. 301,043. (No model.)

To all whom it may concern:

Be it known that I, HENRY L. SHALER, of Deep River, in the county of Middlesex and State of Connecticut, have invented a new 5 Improvement in Dies for Forming Auger-Heads; and I do hereby declare the following, when taken in connection with accompanying drawings and the letter of reference marked thereon, to be a full, clear, and exact 10 description of the same, and which said drawings constitute part of this specification, and represent, in—

Figure 1, a side view of the auger-head, looking toward the gouge-lip and back of the 15 floor-lip; Fig. 2, an opposite side view looking toward the edge of the floor-lip and upon the back of the gouge-lip; Fig. 3, a face view of the head of the auger; Fig. 4, the two parts of the die separated; Fig. 5, a side view of the 20 punch; Fig. 6, a face view of the punch; Fig. 7, a longitudinal central section of the punch on line x x of Fig. 6.

This invention relates to the construction of dies for the formation of double-twist auger- 25 heads, and in which one floor-lip is constructed to form a gouge, while the other floor-lip is flat. Such an auger I represent in Figs. 1, 2, and 3.

A represents the flat floor-lip; B, the spur 30 projecting down from that lip; C, the flat portion of the other lip; D, the gouge portion of the same lip, and E the central screw-point. The object of this construction of auger is that the gouge may cut a groove in 35 advance of the flat floor-lip, whereby the spur will simply have but a shaving to cut instead of running through solid wood, and the chip of the floor-lip will be divided by the groove made by the gouge-lip, and so that the chips 40 which the auger produces will be extremely small, and so as to pass freely out through the twist of the auger, and thereby avoid the friction which necessarily follows the use of an auger having plain floor-lips, or lips alike.

The object of the present invention is to 45 construct dies which may mechanically and accurately shape the head of the auger; and it consists in the construction of dies, as hereinafter described, and particularly recited in 50 the claim.

The die is made in two parts, F, Fig. 4, representing the one part, and G the other part. Each part is constructed with a longitudinal semicircular groove, H, of a diameter corresponding to the diameter of the auger. 55 Diametrically across each part is a rib, I, the inclination of the said rib to the groove corresponding to the twist of the auger and the inclination of the one being the reverse of the other, so that when placed together the space 60 between them will form a recess corresponding to the twist of the auger immediately back of the head end.

The die F is constructed with a second rib, J, inclined corresponding to the rib I, and the face 65 of the rib J constructed with a projection, K, of semicircular shape, which corresponds to the inside of the gouge-lip to be formed. The remainder of the rib corresponds to the shape of the twist from the gouge-lip upward. The 70 other part, G, is constructed with a rib, L, like the rib J, but its inclination is in the opposite direction, as mentioned regarding the other ribs, I J. The under surface of this rib L at M corresponds to the inside of the floor-lip. 75

N, Fig. 5, represents the punch, which is of a diameter corresponding to the groove in the die, which is of cylindrical shape corresponding to the combined grooves of the two parts and so as to enter therein. The face of the 80 punch is constructed with two projections, O P, which correspond to the under or outside of the head, as it is desired that it should come from the die. The one projection, P, has formed in its surface a cavity, R, (see Fig. 6,) 85 which corresponds to the gouge projection K of the rib J of the die. The punch is also formed with a recess, S, in its side corresponding to the spur to be produced. In the center of the punch a conical cavity, T, is formed 90 corresponding to the screw-point of the blank.

The twisted blank, having its head heated, is placed in the dies in the usual manner for introducing augers to heading-dies, and the dies firmly close upon the auger. The punch 95 is driven into the dies against the head end, which upsets the metal between the end of the punch and the corresponding surfaces of the ribs J L of the dies and gives to the blank the gouge shape of one lip, the flat 100

shape of the other lip, and the spur. If, however, the spur is not desirable, the cavity S is omitted.

The projection K on the rib J of the die, 5 which aids in the formation of the gouge-lip, may be omitted, the cavity in the punch forming the proper exterior shape for the gouge portion of the lip, and then the interior or concave side of the gouge may be worked out 10 with tools.

I claim—

The herein-described dies for forming the heads of augers, the said dies consisting of two parts, each part constructed with a longitudinal cylindrical groove of a diameter 15 corresponding to the diameter of the auger to be headed, the said grooves constructed with diagonal ribs I, corresponding to one twist of

the auger back of the head, and the one part, F, constructed with a similar diagonal rib, having its face of the shape desired for the inside 20 of the gouge-lip, the corresponding rib, L, of the other part presenting a flat face, M, upon the opposite side of the groove to the projection K, and a cylindrical follower having its 25 end constructed with two projections, O P, corresponding to the face of the auger-head, the one projection P having a cavity, R, formed therein corresponding to the exterior surface required for the gouge-lip, and the other projection, O, having a surface corresponding to the flat surface M of the other die.
